UNITED STATES PATENT OFFICE.

DAVID SWANGER, OF CANTON, OHIO, ASSIGNOR OF TWO-THIRDS TO
WILLIAM BETZ AND ANTON HAMMERLY, BOTH OF SAME PLACE.

FODDER-CUTTER.

SPECIFICATION forming part of Letters Patent No. 352,960, dated November 23, 1886.

Application filed July 3, 1886. Serial No. 207,069. (No model.)

To all whom it may concern:

Be it known that I, DAVID SWANGER, a citizen of the United States, residing at Canton, in the county of Stark and State of Ohio, have 5 invented certain new and useful Improvements in Fodder-Cutters; and I do hereby declare that the following is a full, clear, and exact description of the same, reference being had to the annexed drawings, making a part 10 of this specification, and to the letters and figures of reference marked thereon, in which—

Figure 1 is a perspective view of my improved straw-cutter, parts being broken away. Fig. 2 is a detached view of the cutter-bar. 15 Figs. 3 are detached views of the main shaft, showing one of the rotary arms attached thereto and the knives placed in position to be properly attached to said rotary arm. Fig. 4 is a detached view of a portion of the lower 20 feed-shaft, showing three sections of the feed-rollers located thereon. Fig. 5 is a detached view of a portion of the upper feed-shaft, showing a section of a feed-roller located thereon. Fig. 6 is a detached view of the bracket and 25 pin for changing the speed of the rollers. Fig. 7 is a top view of a portion of the cutter-bar and one of the rotary arms properly located on the main shaft.

The present invention has relation to fodder- 30 cutters; and it consists in the different parts and combinations of parts hereinafter described, and particularly pointed out in the claims.

Similar letters of reference indicate corresponding parts in all the figures of the drawings. 35

A represents the frame, which may be substantially of the form shown in Fig. 1, and, as shown, is properly braced, so as to rigidly hold the same.

40 To the front or forward end of the frame A are securely attached the plates or bars *a*, said plates or bars being provided with suitable bearings for the main shaft B, said shaft B being located substantially as shown in Fig. 1. 45 To this main shaft B are attached the rotary arms C, and for the purpose of preventing the rotary arms C from turning on the shaft B said shaft is provided with the groove or recess *b*, and the rotary arms C are provided with a 50 corresponding recess, *b'*, and the locking-rod *c*

placed in the position shown in Figs. 3, and for the purpose of securely holding the rotary arms C.

At a given place on the main shaft B the set-screws *c'* are provided, as shown in the drawings. To the ends of the rotary arms C are adjustably attached the knives D. Said knives are substantially of the form shown in the drawings, and are securely attached to the rotary arms C by means of the clamping-bolts 6c *d*, or their equivalents. For the purpose of adjusting the knives D in or out from the main shaft B the slots *e* are provided, as shown in the drawings. The knives D are substantially of the form shown, and, as shown, are provided 65 with the shanks' D', which are integral with the knives D, the knives D being at an angle to the shanks, and when properly attached to the rotary arms C will be at an angle to said arms. The rotary arms C are placed spirally 70 on the main shaft B, as shown in Fig. 1. The object and purpose of so placing the rotary arms C are that but one knife will cut at any one time, thereby causing the fodder to be cut much easier.

75 The cutter-bar E is substantially of the form shown in Figs. 1, 2, and 7, and is securely held in proper position by means of clamping-bolts or their equivalents. I prefer to attach the cutter-bar to the plates or bars *a*. This cutter-bar E is provided with diagonally-arranged teeth *f*, which are formed integral with the bar E. The teeth *f* are so adjusted that their side faces will be in line with the knives D when said knives pass between them. The knives 80 D are placed upon opposite sides of the rotary arms C, as illustrated in Figs. 3, so that the two knives upon one of the rotary arms will pass between two of the teeth *f*.

85 It will be seen that by means of the set-screws *c'*, I am enabled to adjust the knives D to or from the teeth *f*, and thereby regulate the cutter-bar and knives for different kinds of fodder. To one end of the shaft B is rigidly attached the pinion F, which meshes into the 90 wheel G.

To the side of the wheel G is attached or placed the pinion *g*. This pinion *g* may be formed integral with the wheel G, or it may be formed separate and attached in any well- 100

known manner. The pinion *g* communicates motion to the wheel *H*, which is rigidly attached to the lower feed-roller shaft, as shown in Fig. 1, motion being communicated to the upper feed-roller shaft by means of ordinary finger gear-wheels. The wheel *G* and pinion *g* are mounted on a stud or pin, *K*, projecting from one end of a bracket, *L*, having a slot, *M*, for passage of a screw by which it can be adjustably attached to the machine-frame.

The feed-rollers *I* are formed in sections and strung on the shafts, as shown in Figs. 1, 4, and 5. The rollers *I*, designed and calculated for the lower shaft, are fluted or corrugated, as shown in the drawings. The rollers designed and calculated for the upper shaft are provided with the cleats *J*, which are located substantially as shown.

It will be seen that by forming the feed-rollers *I* in sections machines of different widths can be made by increasing or decreasing the number of sections. It will be understood that the feed-rollers proper should be pressed against each other by means of springs.

For the purpose of changing the speed of the feed-rollers *I*, the pinion *g* may be formed of different diameters and adjusted to the wheel *H* by moving the pin *K*, on which the pinion *g* turns, to or from the wheel *H*. For

this purpose the pinion *g* is preferably made 30 separate from the wheel *G*, but capable of being secured thereto in any suitable manner.

Having now fully described my invention, what I claim as new, and desire to secure by Letters Patent, is—

1. The combination, with the diagonally-toothed cutter-bar *E*, of the rotary shaft *B*, the arms *C*, connected in pairs by collars and adjustably secured to said shaft in different planes, thereby forming a spiral thereon, and 40 the knives *D*, adjustably secured to the ends of said arms with their cutting-edges standing at an angle thereto, substantially as described.

2. The combination of the feed-rollers *I*, the toothed cutter-bar *E*, the rotary shaft *B*, having pinion *F*, the arms *C*, mounted on said shaft and provided with knives *D*, the adjustable bracket *L*, having slot *M* and stud *K*, the wheel *G* and pinion *g*, mounted on said stud, and the wheel *H*, attached to the lower feed-50 roller, substantially as described.

In testimony that I claim the above I have hereunto subscribed my name in the presence of two witnesses.

DAVID SWANGER.
